HENRY T. CARTER, 1867

Inventor:

John Whittaker

Aug 24 1867

United States Patent Office.

FRANCIS WHITTAKER, OF SAINT LOUIS, MISSOURI.

Design No. 2,784, dated September 24, 1867.

DESIGN FOR A TRADE-MARK.

The Schedule referred to in these Letters Patent and making part of the same.

TO ALL WHOM IT MAY CONCERN:

Be it known that I, FRANCIS WHITTAKER, of the city and county of Saint Louis, State of Missouri, have originated and produced a new Design for a Trade-Mark, of which the following is a full, clear, and exact description, reference being had to the annexed drawing, making a part of this specification.

My design consists of a five-pointed star, with an illuminated centre, having the initial letter "W" therein, while beneath the star is a shield with a studded border, having upon its face the motto "Fr's Whittaker's Star Sugar-Cured Hams, St. Louis, Mo.," all in combination, and arranged substantially as shown. This is intended to be used as an engraving or as a brand, and when used as the latter the star, shield, and words will have such breaks in them as may be necessary to give the requisite strength to the stencil or other plate by which the impression is made.

What I claim as my invention, and desire to secure by Letters Patent, is—

The design for a trade-mark, substantially as shown and specified.

FRANCIS WHITTAKER.
